Application April 14, 1944, Serial No. 531,029

9 Claims. (Cl. 250—20)

1

This invention is directed to a superregenerative receiver for receiving modulated carrier-frequency wave signals.

A superregenerative receiver, as is well understood in the art, comprises a regenerative oscillatory circuit which is periodically quenched at a frequency much less than that of the generated oscillations. Also, for optimum reception of modulated carrier-frequency wave signals, it is preferable that the quench frequency be much greater than the highest modulation frequency of the received signal desired to be translated. Such a receiver is characterized by a high gain and the oscillations generated in succeeding quench cycles vary in accordance with the amplitude of the exciting signal which initiates the oscillations. In the absence of a received signal, oscillations are initiated by the noise signals present in the receiver circuit. An output signal is frequently derived from the receiver by detecting the generated oscillations. The output signal obtained in this manner during intervals of wave-signal reception includes components representing modulation components of the received signal as well as components introduced by the quenching action and having frequencies harmonically related to the quench frequency. In many installations the described receiver arrangement is satisfactory but, in others, the signal components introduced into the detected output signal by virtue of the quenching action are undesirable.

Consider, for example, an installation in which it is desirable to derive modulation components of a received modulated carrier-frequency wave signal with as high fidelity as possible. This may be necessary in a case where the output signal of the receiver is displayed on the screen of a cathode-ray oscilloscope to enable the intelligence represented by modulation of the received signal to be obtained by visual inspection. In such a case, those signal components of the detected output signal which result from the quenching action are present in the oscilloscope picture and cause the picture to be an unfaithful reproduction of the modulation components of the received signal.

Arrangements have been proposed for reducing the effect of the undesired quench-frequency signal components of the receiver output signal. In one arrangement a small shunt-connected condenser is included in the load circuit of the detector system. Such a condenser has a gradually sloping frequency-response characteristic and fails to suppress sufficiently the low-order unde-

2

sired quench-frequency signal components. In other arrangements a large shunt-connected condenser has been provided in the detector system to suppress all of the undesired quench-frequency components. Such a condenser has a sharply dropping frequency-response characteristic and undesirably attenuates the high-frequency modulation signal components of the received signal. Finally, it has been proposed to utilize a low-pass filter network having a sharp cutoff at a frequency corresponding to about half the quench frequency and a substantially uniform amplitude of response over its pass band. This latter arrangement is ideal from the standpoint of signal selection. However, such a filter network inherently has a nonuniform-frequency time-delay characteristic which results in undesirable distortion of the detected modulation signal components.

It is an object of the invention, therefore, to provide an improved superregenerative receiver for receiving modulated carrier-frequency wave signals and which avoids one or more of the above-mentioned limitations of prior art arrangements.

It is another object of the invention to provide a superregenerative receiver for receiving modulated carrier-frequency wave signals and having an improved fidelity characteristic.

In accordance with the invention, a superregenerative receiver for receiving modulated carrier-frequency wave signals comprises a regenerative oscillatory circuit and means for supplying to the oscillatory circuit a periodic quench voltage to provide superregeneration. The applied quench voltage has a frequency which is low with reference to the carrier frequency of the signal to be received and high with reference to the highest modulation frequency thereof to be translated. The receiver includes means for deriving from the regenerative oscillatory circuit an output signal having desired signal components which represent modulation components of the received signal and having undesired signal components of frequencies harmonically related to the quench frequency. Additionally, there is included in the receiver frequency-selective signal-translating means having maximum attenuation at frequencies corresponding to predetermined harmonics of the quench frequency. This last-named means is utilized for translating the output signal derived from the oscillatory circuit and for suppressing therefrom at least a selected one of the undesired signal components without substantially distorting the desired signal compo-

nents to derive a second signal including the desired signal components. The receiver is also provided with means responsive to the second signal for utilizing the desired signal components.

For a better understanding of the present invention, together with other and further objects thereof, reference is had to the following description taken in connection with the accompanying drawings, and its scope will be pointed out in the appended claims.

In the drawings, Fig. 1 represents a superregenerative receiver, embodying the present invention, for receiving modulated carrier-frequency wave signals; Figs. 2 and 3 comprise graphs utilized in describing the operation of the receiver of Fig. 1; Figs. 4 and 5 represent modifications of a portion of the Fig. 1 arrangement; while Figs. 6a-6f, inclusive, comprise a series of curves used in describing the operation of the Fig. 5 embodiment of the invention.

Referring now more particularly to the drawings, there is represented in Fig. 1 a superregenerative receiver having a linear mode of operation for receiving modulated carrier-frequency wave signals. For convenience of explanation, the receiver may be considered as a component of a radio locating system in which direction-finding information is received as pulse modulation of a carrier-frequency wave signal and reproduced on a cathode-ray tube. The receiver comprises a regenerative oscillatory circuit including a vacuum tube 10 having anode, cathode and control electrodes. Tube 10 has a control electrode-cathode circuit which includes a frequency-determining circuit 11, an oscillation generator 12, and a source of bias voltage E_c . Frequency-determining circuit 11 is provided by a parallel combination of an adjustable inductor 13 and a condenser C shown in broken-line construction since it may be comprised in whole, or in part, of the distributed capacitance of inductor 13, the interelectrode capacitance of the control electrode and cathode of tube 10, as well as other stray capacitance effects associated with inductor 13. The tube 10 has an anode-cathode circuit including an inductor 14 and a source of space current E_b . Inductors 13 and 14 are inductively coupled, as indicated by M_1 , providing a voltage feed-back path from the anode-cathode to the control electrode-cathode circuit of tube 10 for the purpose of sustaining oscillations. The value of bias voltage supplied from source E_c is selected normally to block oscillations in the described regenerative circuit.

Oscillation generator 12 comprises means for supplying to the regenerative circuit a periodic quench voltage of such magnitude as to overcome the blocking voltage E_c at a predetermined point in positive half cycles in order to provide superregeneration. The quench voltage may be of sinusoidal wave form having a frequency which is low with reference to the operating frequency of the regenerative circuit and the carrier frequency of the signal to be received. Also, the quench frequency is preferably high with reference to the highest modulation frequency component, of any received signal, to be translated.

The receiver includes means, consisting of a detector system, for deriving from the regenerative oscillatory circuit an output signal which has desired signal components representing modulation components of the received signal, as well as undesired signal components resulting from the quenching action and having frequencies harmonically related to the quench fre-

quency. This detector system comprises a diode detector 20 and a load circuit provided by an inductor 21 and a parallel combination of a load resistor 22 and a carrier-frequency by-pass condenser 23. The detector system is coupled to the regenerative oscillatory circuit by way of an inductive coupling, indicated by M_2 , between inductors 13 and 21.

There is coupled to the load circuit of the described detector system a frequency-selective signal-translating means 30 having maximum attenuation at frequencies corresponding to predetermined harmonics of the quench frequency. This means is included in the receiver for translating the output signal of the regenerative circuit, as derived in the detector system, and for suppressing therefrom at least one of the undesired quench-frequency signal components without substantially distorting the desired signal components to derive a second signal which includes the desired signal components. Unit 30 includes an amplifier 31, the input circuit of which is coupled to the load circuit of the detector system. A pair of series-resonant trap circuits are connected in shunt relation to the input circuit of amplifier 31. One such trap consists of an inductor 32 and a series-connected condenser 33, while the other is provided by an inductor 34 and a series-connected condenser 35. The first of these traps is resonant, preferably, at a frequency corresponding to the first harmonic, or fundamental, of the quench frequency, while the other is resonant at the second harmonic of the quench frequency.

The receiver also includes means responsive to the above-mentioned second signal derived in unit 30 for utilizing the desired signal components thereof which represent modulation of the received signal. This means, in the illustrated embodiment, consists of an image-reproducing device 40 having an input circuit coupled to the output circuit of amplifier 31. The image-reproducing device may comprise a conventional cathode-ray tube for producing a visual pattern of the wave form of the signal applied to its input circuit. It will be understood that device 40 includes a variable-frequency horizontal sweep-signal source for controlling the horizontal traverse of the electron beam of the cathode-ray tube and a vertical deflecting system responsive to the signal output of amplifier 31 for deflecting the electron beam vertically in accordance with the wave form of the applied signal.

An antenna-ground system 50 including an inductor 51 is utilized for receiving modulated carrier-frequency wave signals to be translated in the receiver. The antenna-ground system is inductively coupled to the regenerative oscillatory circuit, as indicated by M_3 , between inductors 13 and 51.

In considering the operation of the described receiver, the function of unit 30 will be neglected initially and this unit assumed to be a conventional wavesignal amplifier. Where this assumption is made, the system of Fig. 1 comprises a conventional superregenerative receiver and its response to a received signal is illustrated by curves a-d, inclusive, of Fig. 2. Curve a represents a single pulse of a received pulse-modulated carrier-frequency wave signal, assumed to have a fixed pulse duration t and a fixed pulse-repetition frequency. In accordance with characteristic superregenerative operation, the oscillations generated in the circuit of tube 10 in quench 75 cycles which occur within the duration of the

received pulse reach a high amplitude determined by the intensity of the received signal. For the case under consideration, the pulse duration t is such that two quench cycles occur within the pulse interval and the generated oscillations are represented by curve *b*. The oscillations are detected in the detector system, including diode 20, producing, in response to the received pulse, a detected signal output having the wave form of curve *c*. The time constant of resistor 22 and condenser 23 in the load circuit of diode 20 causes the detected signal output, as derived across resistor 22, to have a saw-tooth wave form shown by curve *d*. This signal, after amplification in unit 30, is applied to the input circuit of image-reproducing device 40 and a signal pattern corresponding to the wave form of the applied signal is produced.

From a comparison of curve *d* with the modulation envelope of curve *a*, it is evident that the signal pattern produced is not a faithful representation of the modulation components of the received pulse. This results, in part, from the frequency-response characteristic of the detector load circuit for the assumed condition. This characteristic, shown by broken-line curve *h* of Fig. 3, is such that in addition to desired signal components, which represent modulation of the received signal, undesired signal components attributable to the quenching action are derived in the load circuit of the detector. In this connection it will be noted that the response characteristic is fairly flat over a range extending from zero to approximately one-half the quench frequency f_q , a range which includes all of the desired signal components. One such component, namely the zero-frequency or direct current component, having a wave form which closely approaches the modulation wave form of the received pulse, is represented in curve *e*. It will also be noted from curve *h* that undesired signal components of appreciable amplitude and having frequencies equal to first and second harmonics of the quench frequency are derived in the load circuit of the detector. These signal components are represented by curves *f* and *g*, respectively, and are largely responsible for the discrepancies between the wave form of curve *d* and the modulation of the received signal. Of course, other high-order quench-frequency signal components are present in the signal output of the detector but they are omitted from the drawings for the sake of simplicity.

Considering now the effect of unit 30 on the described response of the receiver, reference is made to full-line curve *j* of Fig. 3. This curve illustrates the frequency-response characteristic of the input circuit of amplifier 31. It will be noted that traps 32, 33 and 34, 35 cause unit 30 to have maximum attenuation for signals harmonically related to the quench frequency. Specifically, these traps are effective to suppress from the output signal of the detector system, as it is translated through unit 30, those undesired signal components of frequencies equal to the first and second harmonics of the quench frequency. This suppressing action, being accomplished by means of frequency-selective trap circuits, causes substantially no phase distortion of the desired signal components. Consequently, the output signal of unit 30, which has been defined above as a second signal, includes the desired signal components and is substantially free of the low-order quench-frequency signal components. Since those undesired signal com-

ponents having frequencies which correspond to the higher-order quench-frequency harmonics have a relatively low amplitude level and may be neglected, this second signal, derived in unit 30 and applied to the input circuit of image-reproducing device 40, has a wave form which closely approaches that of curve *e* in Fig. 2. The resulting pulse pattern produced on the screen of device 40 has substantially the same wave form and represents the modulation of the received signal with relatively high fidelity. Therefore, the direction-finding information conveyed as pulse modulation of the received signal may readily be obtained from observation of the produced signal pattern.

Certain advantages of the described receiver arrangement over those of the prior art mentioned above are clearly demonstrated by its frequency-response characteristic, curve *j*. For example, it will be evident that (1) the receiver has a substantially uniform response over a frequency range including all of the desired modulation components of a received signal; (2) the undesired quench-frequency signal components are suppressed from the receiver output signal; and (3) the receiver circuit has a gradual cut-off characteristic, required to avoid phase distortion of the derived modulation components of the received signal. These factors all contribute to produce a fidelity in the described receiver which surpasses that heretofore attainable with receivers of the superregenerative type.

In Fig. 4 there is represented a modification of the frequency-selective signal-translating means utilized in deriving the above-mentioned second signal from the output signal of the detector system. In this modified form, the frequency-selective signal-translating means 60 comprises a vacuum-tube repeater circuit including a vacuum tube 61 having an input circuit coupled across resistor 22 of the detector system. A pair of parallel-resonant trap circuits are included in the cathode circuit of tube 61. One trap consists of a parallel arrangement of an inductor 62 and a condenser 63 associated with the cathode of tube 61 through an adjustable tap 64. The other trap likewise comprises a parallel combination of an inductor 65 and a condenser 66, and is connected in the cathode circuit through a tap 67. Each trap is individually resonant at a different frequency corresponding to a predetermined harmonic of the quench frequency. Preferably, the resonant frequency of one corresponds to the first harmonic, while the resonant frequency of the other corresponds to the second harmonic of the quench frequency. The trap circuits render the amplifier highly degenerative to signal components of frequencies corresponding to their resonant frequencies, so that the frequency-response characteristic of the Fig. 4 arrangement is also represented by full-line curve *j* of Fig. 3. The Fig. 4 embodiment operates in a manner generally similar to that described in connection with the Fig. 1 arrangement. Taps 64 and 67 are provided to determine the degree of selectivity of the trap circuits and the over-all frequency-response characteristic of signal-translating means 60.

Instead of utilizing trap circuits in the manner indicated in units 30 and 60 of Figs. 1 and 4, respectively, the undesired quench-frequency signal components of the output signal of the detector system may be suppressed through a time-delay filter network, such as represented in unit 70 of Fig. 5. This unit comprises a series of

cascaded vacuum-tube amplifying circuits, only two of which are illustrated in the drawings. The first of these stages includes a vacuum tube 11 having an input circuit coupled to resistor 22 of the detector system and having an output circuit coupled to the next succeeding stage including tube 12. A time-delay reflecting-filter network, in the form of an open-circuited transmission-line section 13, is coupled to the output circuit of amplifier 11 and terminated at its input terminals by an impedance 14. Impedance 14 is selected of such value that this impedance, plus the impedance contributed by the anode-cathode circuit of amplifier 11, constitutes the image or surge impedance of transmission-line section 13. Likewise, an open-circuited transmission-line section 15 is coupled to the output circuit of amplifier 12 and is terminated at its input terminals by its image impedance 16. Transmission-line sections 13 and 15 are selected to have such effective electrical lengths as to delay a signal applied thereto for a predetermined period, as will be described presently.

In considering the operation of the Fig. 5 embodiment, reference is made to Figs. 6a-6f, inclusive. The curve of Fig. 6a represents a single pulse of a received pulse-modulated carrier-frequency wave signal. The curves of Fig. 6b represent the following components of the resulting output signal derived by detector 20: (1) the direct current component, curve e', and (2) the undesired signal component having a frequency corresponding to the first harmonic of the quench frequency, curve f'. The signal represented by Fig. 6b is applied to the input circuit of amplifier 11 and is translated to the output circuit thereof where it is applied to the input terminals of transmission-line section 13. For convenience of illustration, the polarity reversal within the amplifying stage has been neglected. Due to the fact that the remote terminals of the transmission-line section are open circuited, and electrical wave which is the image of the applied wave is reflected therefrom and appears, after a predetermined delay, across the input terminals of the line. Transmission-line section 13 has an electrical length corresponding substantially to a quarter-wave length of the quench frequency so that the reflected signal, shown by the curves of Fig. 6c, is delayed for a period which equals one-half the period of the quench frequency. The delayed and undelayed signals present in the output circuit of amplifier 11 are effectively combined across impedance 14, producing a resultant signal represented by the curves of Fig. 6d. Due to the prescribed delay period, undesired signal components having frequencies that correspond to the odd harmonics of the quench frequency are substantially eliminated from this resultant signal. The elimination of such undesired components causes that signal component, curve g', having a frequency equal to twice the quench frequency to be the predominant undesired component in the resultant signal of Fig. 6d. This signal is, in turn, translated by amplifier 12 where a similar delaying and combining process takes place. In this case, however, transmission-line section 15 has an electrical length equal to an eighth-wave length of the quench frequency. The combining of the delayed signal of Fig. 6e and the undelayed signal of Fig. 6d in the output circuit of amplifier 12 produces the resultant signal of Fig. 6f from which undesired signal components which have a frequency corresponding to twice the quench frequency are effectively sup-

pressed. Also, all signal components having frequencies of twice the odd harmonics of the quench frequency are suppressed by the combining step in amplifier 12. Curve s of Fig. 6f represents the signal applied to the image-reproducing device 40 from unit 10. The wave form of this signal closely approaches the modulation envelope of the received signal.

In describing the several modifications of the invention, mention has been made of removing those undesired signal components which have frequencies equal to the first and second harmonics of the quench frequency. In actual installations it is found that the removal of such undesired components is sufficient to produce a reasonably accurate pictorial representation of the desired modulation components of the received signal. If desired, others of the undesired quench-frequency signal components may be selectively eliminated. Theoretically, at least, an improved result may be obtained by multiplying the number of trap circuits utilized in the frequency-selective units 30 and 60 of Figs. 1 and 4, respectively. Likewise, an improved result may be obtained with the Fig. 5 embodiment by increasing the number of delaying and combining steps. For example, by including four cascaded amplifying stages in unit 10, all undesired signal components up to and including those which have a frequency corresponding to the eighth harmonic of the quench frequency may be eliminated. The components eliminated in the successive stages and the time delays involved in the individual reflecting-filter networks are given in the following table:

Step No.	Delay of filter network (in fractions of quench-frequency wave length)	Quench-frequency signal components suppressed (multiples of quench frequency)
40		
45	1/16	1-3-5-7
45	1/8	2-6
45	1/4	4
45	1/16	8

The time-delay filter arrangements of Fig. 5 may take any of a variety of forms. For example, these arrangements may comprise a low-pass filter of an appropriate number of sections; wound or loaded lines; open-wire parallel-conductor lines; or an equivalent parallel group of series-tuned trap circuits.

It will be understood that the invention is subject to a general application and is not to be limited to the reception of pulse-modulated carrier-frequency wave signals, as particularly described above. In the reception of any modulated carrier-frequency wave signal, undesired quench-frequency components are introduced by the quenching action and may be suppressed through the use of arrangements of the type disclosed. Also, it will be apparent that image-reproducing device 40 may be replaced by any suitable utilizing circuit for utilizing the derived signal components of received signals.

In addition to providing high fidelity in a superregenerative receiver, the described invention is particularly useful in connection with a wave-signal transpondor system of the regenerative type. By "wave-signal transpondor system" is meant a wave-signal translating system including a receiver and a transmitter so arranged that a predetermined reply is transmitted in

response to a received interrogating signal. Where the receiver is of the superregenerative type, it is common practice to include a control arrangement for controlling the sensitivity thereof. Such a control arrangement may derive a gain-control voltage in response to the noise-signal components included in the output signal of the receiver obtained during intervals when no desired signal is being received. In such a case, a received continuous-wave signal normally causes the transmitter to send out a continuous succession of answer signals, which is an undesirable operating condition. This condition may be precluded by deriving an output signal from the receiver in accordance with the teachings of this invention, and utilizing this output signal to control the operation of the transmitter.

While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A superregenerative receiver for receiving modulated carrier-frequency wave signals comprising, a regenerative oscillatory circuit, means for supplying to said circuit a periodic quench voltage to provide superregeneration, said quench voltage having a frequency which is low with reference to the carrier frequency of the signal to be received and high with reference to the highest modulation frequency thereof to be translated, means for deriving from said regenerative oscillatory circuit an output signal having desired signal components representing modulation components of said received signal and having undesired signal components of frequencies harmonically related to said quench frequency, frequency-selective signal-translating means having maximum attenuation at frequencies corresponding to predetermined harmonics of said quench frequency for translating said output signal and for suppressing therefrom at least a selected one of said undesired signal components without substantially distorting said desired signal components to derive a second signal including said desired signal components, and means responsive to said second signal for utilizing said desired signal components.

2. A superregenerative receiver for receiving modulated carrier-frequency wave signals comprising, a regenerative oscillatory circuit, means for supplying to said circuit a periodic quench voltage to provide superregeneration, said quench voltage having a frequency which is low with reference to the carrier frequency of the signal to be received and high with reference to the highest modulation frequency thereof to be translated, means including a detector system for deriving from said regenerative oscillatory circuit an output signal having desired signal components representing modulation components of said received signal and having undesired signal components of frequencies harmonically related to said quench frequency, frequency-selective signal-translating means having maximum attenuation at frequencies corresponding to predetermined harmonics of said quench frequency for translating said output signal and for suppressing therefrom at least a selected one of said undesired signal components without substantially dis-

torting said desired signal components to derive a second signal including said desired signal components, and means responsive to said second signal for utilizing said desired signal components.

3. A superregenerative receiver for receiving modulated carrier-frequency wave signals comprising, a regenerative oscillatory circuit, means for supplying to said circuit a periodic quench voltage to provide superregeneration, said quench voltage having a frequency which is low with reference to the carrier frequency of the signal to be received and high with reference to the highest modulation frequency thereof to be translated, means for deriving from said regenerative oscillatory circuit an output signal having desired signal components representing modulation components of said received signal and having undesired signal components of frequencies harmonically related to said quench frequency, frequency-selective signal-translating means having maximum attenuation at frequencies corresponding to predetermined harmonics of said quench frequency for translating said output signal and for suppressing therefrom at least undesired signal components having a frequency corresponding to the first harmonic of said quench frequency without substantially distorting said desired signal components to derive a second signal including said desired signal components, and means responsive to said second signal for utilizing said desired signal components.

4. A superregenerative receiver for receiving modulated carrier-frequency wave signals comprising, a regenerative oscillatory circuit, means for supplying to said circuit a periodic quench voltage to provide superregeneration, said quench voltage having a frequency which is low with reference to the carrier frequency of the signal to be received and high with reference to the highest modulation frequency thereof to be translated, means for deriving from said regenerative oscillatory circuit an output signal having desired signal components representing modulation components of said received signal and having undesired signal components of frequencies harmonically related to said quench frequency, frequency-selective signal-translating means having maximum attenuation at frequencies corresponding to predetermined harmonics of said quench frequency for translating said output signal and for suppressing therefrom at least a selected one of said undesired signal components without substantially distorting said desired signal components to derive a second signal including said desired signal components, and means responsive to said second signal for utilizing said desired signal components.

5. A superregenerative receiver for receiving modulated carrier-frequency wave signals comprising, a regenerative oscillatory circuit, means for supplying to said circuit a periodic quench voltage to provide superregeneration, said quench voltage having a frequency which is low with reference to the carrier frequency of the signal to be received and high with reference to the highest modulation frequency thereof to be translated, means for deriving from said regenerative oscillatory circuit an output signal having desired signal components representing modulation components of said received signal and having undesired signal components of frequencies harmonically related to said quench frequency, frequency-selective signal-translating means including at

least one trap circuit resonant at a frequency corresponding to a predetermined harmonic of said quench frequency for translating said output signal and for suppressing therefrom undesired signal components having a frequency corresponding to said predetermined harmonic of said quench frequency without substantially distorting said desired signal components to derive a second signal including said desired signal components, and means responsive to said second signal for utilizing said desired signal components.

6. A superregenerative receiver for receiving modulated carrier-frequency wave signals comprising, a regenerative oscillatory circuit, means for supplying to said circuit a periodic quench voltage to provide superregeneration, said quench voltage having a frequency which is low with reference to the carrier frequency of the signal to be received and high with reference to the highest modulation frequency thereof to be translated, means for deriving from said regenerative oscillatory circuit an output signal having desired signal components representing modulation components of said received signal and having undesired signal components of frequencies harmonically related to said quench frequency, a vacuum-tube repeater circuit including at least one trap circuit resonant at a frequency corresponding to a predetermined harmonic of said quench frequency for translating said output signal and for suppressing therefrom undesired signal components having a frequency corresponding to said predetermined harmonic of said quench frequency without substantially distorting said desired signal components to derive a second signal including said desired signal components, and means responsive to said second signal for utilizing said desired signal components.

7. A superregenerative receiver for receiving modulated carrier-frequency wave signals comprising, a regenerative oscillatory circuit, means for supplying to said circuit a periodic quench voltage to provide superregeneration, said quench voltage having a frequency which is low with reference to the carrier frequency of the signal to be received and high with reference to the highest modulation frequency thereof to be translated, means for deriving from said regenerative oscillatory circuit an output signal including desired signal components representing modulation components of said received signal and undesired signal components having frequencies harmonically related to said quench frequency, means for delaying said output signal for a period substantially equal to an odd-integral multiple of one-half period of a predetermined harmonic of said quench frequency without appreciably changing the wave form of the delayed signal and for combining the delayed with the undelayed output signal to develop a resultant signal which includes said desired signal components and which is substantially free of said undesired signal components having a frequency corresponding to said predetermined harmonic, and means responsive to said resultant signal for utilizing said desired signal components.

8. A superregenerative receiver for receiving modulated carrier-frequency wave signals com-

prising, a regenerative oscillatory circuit, means for supplying to said circuit a periodic quench voltage to provide superregeneration, said quench voltage having a frequency which is low with reference to the carrier frequency of the signal to be received and high with reference to the highest modulation frequency thereof to be translated, means for deriving from said regenerative oscillatory circuit an output signal including desired signal components representing modulation components of said received signal and undesired signal components having frequencies harmonically related to said quench frequency, means including a time-delay filter for delaying said output signal for a period substantially equal to an odd integral multiple of one-half period of a predetermined harmonic of said quench frequency without appreciably changing the wave form of the delayed signal and for combining the delayed with the undelayed output signal to develop a resultant signal which includes said desired signal components and which is substantially free of said undesired signal components having a frequency corresponding to said predetermined harmonic, and means responsive to said resultant signal for utilizing said desired signal components.

9. A superregenerative receiver for receiving modulated carrier-frequency wave signals comprising, a regenerative oscillatory circuit, means for supplying to said circuit a periodic quench voltage to provide superregeneration, said quench voltage having a frequency which is low with reference to the carrier frequency of the signal to be received and high with reference to the highest modulation frequency thereof to be translated, means for deriving from said regenerative oscillatory circuit an output signal including desired signal components representing modulation components of said received signal and undesired signal components having frequencies harmonically related to said quench frequency, means including a time-delay reflecting-filter network for delaying said output signal for a period substantially equal to an odd-integral multiple of one-half period of a predetermined harmonic of said quench frequency without appreciably changing the wave form of the delayed signal and for combining the delayed with the undelayed output signal to develop a resultant signal which includes said desired signal components and which is substantially free of said undesired signal components having a frequency corresponding to said predetermined harmonic, and means responsive to said resultant signal for utilizing said desired signal components.
